UNITED STATES PATENT OFFICE.

WILLIAM H. MATTHIES, OF HACKENSACK, AND WALTER P. ALBERT, OF EAST ORANGE, NEW JERSEY, ASSIGNORS TO WESTERN ELECTRIC COMPANY, INCORPORATED, OF NEW YORK, N. Y., A CORPORATION OF NEW YORK.

TELEPHONE-EXCHANGE SYSTEM.

Application filed November 30, 1923. Serial No. 677,834.

To all whom it may concern:

Be it known that we, WILLIAM H. MATTHIES and WALTER P. ALBERT, citizens of the United States of America, residing at Hackensack, in the county of Bergen and State of New Jersey, and East Orange, in the county of Essex and State of New Jersey, respectively, have invented certain new and useful Improvements in Telephone-Exchange Systems, of which the following is a full, clear, concise, and exact description.

This invention relates to telephone exchange systems and especially to systems employing automatic switches for the establishment of connections.

The invention has for its object an improvement in the means of connecting a calling subscriber's line with any one of a plurality of called subscribers' lines.

20 A feature of the invention relates to a small telephone system wherein each line may be paired with every other line and trunk, and a connecting device, such as a relay, which is individual to each pair is used for connecting them together.

Further features and advantages will become apparent from a detailed description of the invention.

The drawings, when arranged in the order 30 illustrated in Fig. 5 discloses a preferred method of using the invention.

Fig. 1 shows in connection with a subscriber's line circuit, a register switch for recording the designation of called lines, and a number of transfer relays. In addition a portion of the start circuit for causing the association of the calling line with an idle central office trunk is shown, as also are a number of individual connecting 40 relays.

Fig. 2 illustrates substantially similar circuits and apparatus to those shown in Fig. 1.

Fig. 3 discloses a central office trunk with the controlling apparatus therefor for allowing calls to be made to a central office; and also a line for completing calls to an attendant, whose talking and connecting apparatus is shown in that portion of the figure within the broken line.

50 Fig. 4 illustrates in schematic form an outline of the plan of using the invention.

Referring to Fig. 4 there are shown a plu-

rality of subscribers' lines with dialing apparatus and register switches, each individual to one of said lines. In conjunction 55 with the register switch there are a number of connecting relays associated with each subscriber's line and intended to be operated according to the position assumed by the individual register switch which is controlled 60 or set by impulses transmitted by the calling subscriber. In this figure is also shown an arrangement for interconnecting any two subscribers' lines by means of a connecting relay which is individual to both of said 65 lines.

A call from one local station to another is accomplished by the calling subscriber dialing the numerical designation of the desired line. Calls to the central office are 70 completed by dialing a special code which causes the association of the calling subscriber's line with an idle one of a number of central office trunks, at the same time releasing the line circuit with its associated 75 controlling apparatus and registering mechanism, and allowing battery to be supplied from the central office. Provision is made for placing the release of the connection under the control of the central office 80 operator.

An incoming call from a central office is received by the attendant and may be extended to any desired station by simply operating the proper stations key whereupon 85 she receives a signal notifying her whether the local subscriber's line is busy or idle. If the called party is connected with another local subscriber the attendant by means of a no-test key can break in on the established 90 connection and notify the local called subscriber that a central office call is waiting.

The attendant is provided with a line circuit for enabling any local subscriber to signal her. The attendant may also originate 95 calls either to a central office or to any one of the local subscribers. The latter is accomplished by dialing the local subscriber's number over the attendant's line circuit.

The subscriber's line circuit with its controlling apparatus and registering mechanism used on local calls is disconnected upon calls to the central office, and by means of a common start circuit it is impossible for two 100

or more calling parties to become connected with the same central office trunk.

The general description of how a call is completed between local subscribers will now be given, reference being had to Fig. 4, wherein are illustrated a number of subscribers' stations 401, 402, 403, etc., and a number of subscribers' lines 420, 421, 422, etc. Associated with each calling line and individual thereto is controlling apparatus 430 represented schematically and also a register switch. The register switch 410 for instance is associated with line 420. The register switch comprises a plurality of multiple banks and cooperating wipers. The terminals of the multiple banks are connected by means of conductors 431 to the windings of connecting relays 412, 413, 414, etc., the particular one of which, when operated, connects the calling subscriber's line directly with the called subscriber's line, which connection is independent of the register switch.

The calling subscriber, upon removing his receiver closes a circuit for operating the individual register switch 410 under control of his sending dial, and depending upon the value of the first digit dialed one or a number of transfer relays is operated. Upon the completion of the dialing of the second digit, the register switch is set upon the terminals corresponding to the called line and thereupon a circuit is closed to operate the proper one of the connecting relays 412, 413, 414, etc. For example, assume that the subscriber of line 420 desires to converse with the subscriber of line 422. When the calling subscriber has completed his dialing and the register switch individual to his line has been set upon the terminal corresponding to line 422 a circuit is closed to operate the connecting relay 413 which is individual to lines 420 and 422, thereby connecting line 420 directly with line 422, through the front contacts of this connecting relay.

For the purpose of allowing each of the local subscribers to communicate with the central office 445, each line is provided with a duplicate set of connecting relays 417, 418, etc., corresponding to relays 412, 413, etc. In this case, the connecting relays are each individual to a line and a central office trunk. For example, assuming that there are ten central office trunks, then each subscriber's line is equipped with ten relays similar to relay 417. When the central office code is dialed by a local subscriber, the register switch 410 is correspondingly positioned and causes a connecting relay, for example, relay 418 to operate. Relay 418 is individual to the pair formed by the calling line 420 and the first available office trunk, in this case trunk 447. Similarly, each of the other local lines has associated

therewith sets of relays such as relays 442, 443, 444, etc.

Local call.

A detailed description of the method of connecting two local lines will now be given. For this purpose, let it be assumed that the subscriber of line 101, Fig. 1, whose number is 16, desires to talk with the subscriber at line 202, whose number is 15. When the calling subscriber removes his receiver from the switchhook, a circuit is closed to operate relay 102 from battery through the right-hand winding of said relay, inner right back contact of relay 103, middle right back contact of relay 104, over the ring side of the calling line through the subscriber's set, thence over the tip side of the line, through the inner right back contact of relay 104 to ground through the left winding of relay 102. Relay 102 becomes energized and closes a circuit for the slow-releasing relay 105 from battery through the winding of the said relay, front contact and armature of relay 102, conductor 150, normal terminal and brush 140 of register switch 100, conductor 151 to ground at the left inner armature and back contact of relay 106. The operation of relay 105 closes an obvious operating circuit for relay 106. Relay 106 upon attracting its armatures closes a substitute holding circuit for relay 105 which circuit is independent of register switch 100 and may be traced as follows: from battery through the winding of relay 105, right front contact and armature of relay 102, left back contact and armature of relay 104 to ground at the left inner armature and front contact of relay 106. The circuit is now in condition to receive the first set of impulses.

The subscriber upon manipulating his dial for the tens digit, which in this case, is represented by one impulse, releases relay 102 thereupon closing a circuit to operate stepping magnet 108 as follows: battery through the winding of slow releasing relay 107, winding of stepping magnet 108, conductor 152, left back contact and armature of relay 109, outer left armature and front contact of relay 106, right armature and back contact of relay 102, left back contact and armature of relay 104 to ground at the left inner armature and front contact of relay 106. Where the line circuit is reclosed stepping magnet 108 having received one impulse, positions brushes 140, 141, 142 upon the number one set of terminals. Following the transmission of the tens series of impulses, the slow to release relay 107 releases closing a circuit as follows: from ground through the left inner armature and front contact of relay 106, left winding of relay 109, conductor 153, back contact and armature of relay 107, conductor 154, brush 141

and No. 1 right hand terminal of register switch 100, conductor 155 to battery through the winding of relay 113. Relay 113 closes a locking circuit for itself from ground at 5 the armature and front contact of relay 105, right inner armature and front contact of relay 113 to battery. It will be observed that if the called line had 2 as its tens digit the register switch 100 would have been 10 positioned on the No. 2 set of terminals, and instead of operating a single recording relay as 113, a set of recording relays as 110, 111 would have been operated.

The calling subscriber next transmits the 15 set of impulses corresponding to the units digit of the called line. In this case, since the called number has a units digit of 5 the line circuit will be opened five times and relay 102 will release accordingly stepping 20 register switch 100 to the set of terminals 161, 162 corresponding to the units digit of the called line. If the number of the called line was 24 instead of 15, the brushes of the 25 register switch 100 at the end of the units dialing would be resting on the same set of terminals which were used in the case of the called line 15, but in this case, recording relays 110 and 111 operate in place of recording relay 113.

30 Relay 107 releases a second time when the subscriber has dialed the units digit of the called line designation. Should the line which is being called be busy, relay 206 will be in an operated condition and the calling subscriber will receive a busy signal over the following circuit: from a tone source 222, through the right armature and front contact of relay 206, conductor 254, lower middle armature and back contact of relay 111, terminal 162 of register switch 100, brush 141, armature and back contact of relay 107, conductor 153, left inner armature and back contact of relay 109, condenser 112 to the ring side of the line, thence through the 45 substation loop, returning over the tip side of the line, to ground through the left winding of relay 102.

If, however, the called line is idle a circuit is closed, when relay 107 releases the 50 second time, for operating relay 203 which is individual to the called line. This circuit may be traced from ground through the left inner armature and front contact of relay 106, left winding of relay 109, conductor 153, armature and back contact of relay 107, brush 141, terminal 162 of register switch 100, the lower middle armature and back contact of relay 111, conductor 254, right armature and back contact of relay 206, through the winding of relay 203 to battery. Relays 109 and 203 operate in this 55 circuit. At the same time a circuit is closed to operate the connecting relay 220 which is common to lines 15 and 16 as follows: 60 from battery through the winding of relay 220, conductor 255, lower middle armature and back contact of relay 110, terminal 161 of register switch 100, brush 142, conductor 158, right armature and front contact of relay 109, through the right hand winding 70 of said relay to ground at the left inner armature and front contact of relay 106. The operation of relay 220 connects the calling subscriber's line through the contacts of said relay directly to the called subscriber's line. 75 The operation of relay 220 also provides a locking circuit for relay 203 as follows: battery through the winding of relay 203, left inner armature and front contact of said relay, armature and contact of relay 214 to 80 ground at the lower inner armature and front contact of relay 220.

When relay 203 operates subsequent to the completion of dialing, the called subscriber's bell is rung from a source of ringing current 213 through winding of relay 214, thence to the ring side of the line, through the subscriber's ringing apparatus and back over the tip side of the line to ground through the left winding of relay 90 201. The operation of relay 203 also closes an obvious circuit for relay 205 which in turn operates relay 206 to render this line busy to other calling stations.

When the called subscriber removes his 95 receiver from the switchhook, the resistance of the circuit including relay 214 is reduced so that the latter now operates and breaks the locking circuit for relay 203 which releases and disconnects ringing current from 100 the called line. The calling subscriber can now hold conversation with subscriber of line 202.

From an inspection of the circuits, it will be obvious that had the called subscriber's 105 number contained a tens digit 2, a connecting relay other than 220 would have been operated, through a front contact of transfer relays 110 and 111 instead of through back contacts of these relays. Thus by discriminating as to the tens digit and thereby 110 operating certain of the transfer relays 109, 110 and 111 a limited number of contacts on the register switch 100 can serve for connecting with a greater number of called 115 lines.

Following conversation when the calling subscriber replaces his receiver on the switchhook, line relay 102 releases, thus opening the operating circuit of slow releasing relay 105. When relay 105 releases, it in turn releases relay 106 and relay 113. When relay 106 releases, a circuit is closed to restore register switch 100 to its normal 125 position as follows: Battery through the winding of relay 107, winding of stepping magnet 108, armature and contact thereof, conducting segment 160, brush 140, conductor 151 to ground at the left inner armature and back contact of relay 106. Switch 100 130

thus steps itself by means of its interrupter contacts to its normal position. The release of relay 106 caused the successive release of relay 109 and connecting relay 220, thus establishing connection between the two stations. When the called subscriber hangs up his receiver he releases the remainder of the connection by releasing relays 201, 205 and 206 in succession.

From the foregoing description it will be clear that if the subscriber of line 202 had initiated the call for the purpose of connecting with subscriber's line 101, the register switch 200 would operate. In this case the same connecting relay 220 would be energized since this is the only one of all the connecting relays which is common to lines 15 and 16. In a similar manner another connecting relay as 221 would serve to interconnect lines having numbers 15 and 22 regardless whether line 15 was originating or terminating the call.

Trunk circuit originating calls.

Should a local subscriber desire connection with the central office the procedure is similar for that described for a local call as far as the point where the register switch is set corresponding to the units digit. However, in this case, a special code is dialed for associating the calling line with a central office trunk. In the case illustrated, this code is represented by the number 11. When, therefore, a subscriber as the subscriber of line 202 dials the code 11, the register switch 200, at the completion of dialing has its brushes 241 and 242 positioned upon terminals 261 and 262. Since the tens digit of the special office code is 1, transfer relay 212 alone will be operated. The operation of relay 212 closes a circuit for trunk relay 216, traceable from battery at the armature and back contact of relay 217, left winding of relay 216, left armature and front contact of relay 212, brush 242, conductor 259, right armature and front contact of relay 209 and right hand winding thereof to ground at armature of relay 206. Relay 216 operates and closes a locking circuit for itself as follows: from battery through the right hand winding, right inner armature and front contact of said relay, to ground at the armature and front contact of relay 205. The operation of relay 216 also closes an obvious operating circuit for relay 217. Relay 217 which is common to a number of central office trunks, upon operating removes battery from conductor 258 thus preventing any other trunk relay similar to relay 216 from operating and associating another calling line with this particular trunk. Assuming that trunk 355 is idle, starting relay 301 individual thereto is operated, over a circuit traceable from battery through its winding, left inner armature and back con-

tact of relay 302, conductor 341, to ground at the left outer armature and front contact of relay 216. If, however, trunk 350 had been busy relay 302 individual thereto, would be operated and the starting wire 341 would be extended through the locking contacts of relay 302 to the next starting relay similar to relay 301 associated with the next idle trunk. Should all the central office trunks be busy, relay 303 will operate from battery through its winding, left inner front contacts of intermediate relays similar to relay 302, to ground at the left outer armature and front contact of relay 216. The operation of relay 303 therefore, will cause a distinctive tone to be sent back to the calling subscriber from a source of tone 314 through the armature and front contact of relay 303, conductor 342, right outer armature and front contact of relay 212, terminal 262 of register switch 200, brush 241, armature and back contact of relay 207, left inner armature and back contact of relay 209, condenser 210 to the ring side of the calling line, thence through apparatus at station 202, notifying the calling subscriber that all the central office trunks are busy.

Returning to the point where starting relay 301 was operated in connection with the first idle central office trunk, connecting relay 218, which is common to this trunk and calling line 15, was operated as follows: from battery at the left armature and contact of relay 301, conductor 343, upper winding of relay 218 to ground at the left inner armature and front contact of relay 216. Relay 301 connects direct ground at its right armature and front contact to the tip side of the trunk which serves to signal the central office operator. At the same time the low resistance bridge 327 was placed across the trunk. The central office operator upon observing the signal plugs in on this trunk and in a well known manner places battery on the tip side, and ground on the ring side of the trunk as a result of which relay 306 operates. Relay 306 closes an obvious operating circuit for slow releasing relay 307 which in turn closes an obvious circuit for relay 308. Relay 308 closes an obvious operating circuit for relay 309. Relay 309 at its right armature and front contact lights busy lamp 310 in parallel with the right hand winding of relay 302 which operates and transfers the starting circuit to the next idle trunk. The lighting of lamp 310 serves as a signal to the attendant that the associated central office trunk is busy. Relay 309 at its left armature and front contact also closes a locking circuit for connecting relay 218 as follows: from ground through the left armature and contact of relay 309, normal contacts of relay 335, left armature and back contact of relay 338, conductor 344, inner armature and front con-

tact of relay 218, through the lower winding of said relay in series with the winding of relay 204 to battery. Relay 204 operates in this circuit and disconnects the subscriber's line from the P. B. X. link and its associated relays and register mechanism. The calling line is now connected directly with a central office trunk, and since relay 313 is bridged across the trunk, it operates in series with the subscriber's set. Subsequent to answering by the central office operator, relay 323 operates from battery through its winding, left outer armature and back contact of relay 335, right armature and front contact of relay 313 to ground at the left armature and front contact of relay 308. Relay 323 also locks in a circuit from battery through its winding, right outer armature and front contact to ground at relay 308. Relay 323 in operating, connects the calling subscriber's line through the inner armatures and front contacts of said relay directly with the central office trunk, and the calling subscriber may either give the number of the desired line to the central office operator in the case of a manual office, or dial the central office number in the case of a mechanical office.

Disconnection.

Following conversation, when the calling subscriber replaces his receiver, supervisory relay 306 releases, and after an interval relays 307 and 308 release. Relay 309, however, being slow to release is held operated from ground at the armature of relay 316 which is bridged across the trunk upon the release of relay 308. The complete release of the connection, therefore, is under the control of relay 316 which in turn is controlled by the central office operator.

Incoming calls.

When a central office operator plugs in on a trunk with a cord circuit, relay 316 operates from a source of battery at the central office over the tip side of the trunk, left normal contact of key 330, right normal contact of key 332, the right outer armature and back contact of relay 308 through both windings of relay 316 in series to the ring side of the trunk, right normal contact of key 330 and thence over the ring side of the trunk to a source of ground at the central office. The operation of relay 316 closes an obvious operating circuit for relay 309 which in turn lights the busy lamp 310 as hereinbefore described. Relay 302 also operates in this circuit and renders the associated trunk busy by extending the start wire 341 to the next idle trunk.

When the central office operator applies ringing current to the trunk, a circuit is closed for ringing relay 315 which operates, since its left hand winding is bridged across

the trunk. Relay 315 locks over a circuit traceable from battery through the right hand winding, right armature and front contact of said relay, right armature and back contact of relay 318, left normal contacts of relay 320 to ground at the right armature and front contact of relay 309. The line lamp 312 also lights when relay 315 locks. The lighting of lamp 312 serves as a signal to the attendant that a central office call is awaiting connection. The talk key 331 is thereupon operated closing an obvious operating circuit for relay 318 which locks through its right armature and front contact through the left normal contacts of relay 320, to ground at the right armature and front contact of relay 309. The operation of relay 318, extinguishes the lamp 312 and releases relay 315. The operation of relay 318 also places retardation coil 319 in parallel with the right hand winding of relay 316 which is bridged across the trunk.

The attendant by operating the talking key 331 connects the talking set 350 through the normal contacts of relay 337 across the trunk, for the purpose of receiving the number of the desired station. Upon receiving the designation of the station, the operator throws key 260 which is individual thereto. It will be observed that when keys 260 and 331 are thrown, relays 335 and 337 operate from battery through the windings of said relays in parallel, left outer contact of key 331, to ground at the left contact of stations key 260. If the desired station be busy the attendant will receive a busy tone as follows: from source of tone 222, right armature and front contact of relay 206, right contact of key 260, conductor 345, left outer armature and back contact of relay 336, condenser 351, right armature and back contact of relay 338, ring side of the trunk, middle front contacts of relay 337 through the attendant's talking set, through the inner contacts of relay 337, right normal contacts of relay 323, to battery through the right winding of relay 318. In this case, the attendant may break in on the established connection to inform the subscriber at station 202 that a central office call is waiting. For this purpose the attendant operates the key 361, and relay 338 operates from battery through its winding, left outer armature and front contact of relay 337 to ground at key 361. The operation of relay 338 cuts off the busy tone from the attendant's set and with station key 260 operated, a circuit is closed to operate connecting relay 218 associated with the subscriber's line as follows: from ground at the contact of key 360, right outer armature and front contact of relay 335, left armature and front contact of relay 338, conductor 347, middle contact of key 260, 125

upper winding of relay 218 to battery at the left inner armature and front contact of relay 335. The operation of relay 218 therefore connects the attendant's talking set directly with the subscriber's set at station 202. It will be observed that when relay 337 operated, the attendant's talking set 350 was transferred from the central office end of the trunk to the local end of the same 10 trunk. The attendant may now inform subscriber 202 that a call is awaiting him from the central office.

If, when the attendant operated key 260, the associated station had been idle, relay 15 206 would be normal and a circuit would be closed from battery through the winding of relay 203, right armature and back contact of relay 206, right contact of key 260, to ground through the left hand winding 20 of relay 336. Relay 336 operates and closes a locking circuit from battery through its right hand winding, right armature and front contact, right outer armature and front contact of relay 335 to ground at key 25 360. The operation of relay 336 closes the following circuit: from ground at the left armature and front contact of relay 309, left inner armature and front contact of relay 336, conductor 347, middle contact of key 260, upper winding of relay 218 to battery at the left inner armature and contact 30 of relay 335. Relay 218 locks in a circuit from battery through the winding of relay 204, lower winding, inner armature and front contact of relay 218, conductor 344, left armature and back contact of relay 338, right outer armature and front contact of relay 335 to ground at key 360. The attendant is now in direct communication with 35 the called station, ringing current having been applied to the called line when relay 203 operated and locked, in the manner already described for a local call. The attendant may now release the talk key 331, and station key 260. The release of these 40 two keys releases relays 337, 335, and relay 313. When relay 335 releases, guard lamp 311 is lighted from battery through the lamp 311, left outer armature and front contact 45 of relay 318, right inner armature and back contact of relay 320, right inner armature and back contact of relay 335 to ground at the left armature and front contact of relay 309. The lamp 311 remains lighted in this 50 circuit until the called subscriber has answered.

When the called subscriber removes his receiver from the switchhook, relay 313 re-operates as hereinbefore described. The 60 operation of relay 313 causes the operation of relay 323, in a circuit traceable from battery through the winding of relay 323, left outer armature and back contact of relay 335, left armature and front contact of relay 313 to ground at the armature and con-

tact of relay 316. Relay 323 closes a locking circuit for itself, from battery through its winding, right outer armature and front contact to ground at the armature of relay 316, at the same time releasing relay 313. 70 The release of relay 313 closes the following circuit: from battery through the winding of relay 320, left middle armature and front contact of relay 318, left outer armature and front contact of relay 323, right 75 armature and back contact of relay 313 to ground at the armature of relay 316. Relay 320 operates and locks to ground at the left armature and front contact of relay 309. Relay 320 also causes guard lamp 311 to be 80 extinguished which serves as a signal to the attendant that the called party has answered. Ringing current was cut off when relay 214 operated subsequent to the called subscriber removing his receiver from the 85 switchhook. When relay 203 operates as above described it closes an obvious circuit for slow releasing relay 205 which in turn operates relay 206 thus rendering this line busy to any other calling station. 90

Disconnection is substantially the same as before described in connection with a local subscriber calling the central office, the release of the connection being under the control of the central office operator who can 95 keep relay 316 operated and in turn control the locking circuit of connecting relay 218.

In order that the attendant may be called by a subscriber at any local station, she is provided with a line circuit 349, which has controlling and registering mechanism similar to that shown in the line circuits illustrated in Figs. 1 and 2. When ringing current is applied to the line 349 as a result of such call, relay 353 operates to light the 100 lamp 352 as a signal that a local subscriber desires to converse with the attendant. She answers by operating the key 356 which causes her talking set to be placed in direct connection with the calling subscriber's line. The attendant at the station is provided with dialing apparatus which she manipulates when she wishes to initiate a call to any local subscriber. Should the attendant desire to leave the position, key 105 362 is actuated. Accordingly, when relay 353 operates upon the application of ringing current to the line 349, lamp 352 lights and relay 364 operates in parallel with the right hand locking winding of relay 353 to ground at the contacts of key 356. Relay 110 364 closes a circuit through the contacts of key 362 and the buzzer 363 to battery. The buzzer 363 gives an audible signal for the purpose of attracting the attention of the attendant. It should also be noted that relay 366 operates in parallel with the right hand locking winding of relay 315. Relay 115 366 performs similar functions to relay 364 and is operated when the attendant is away 120 130

from the position when an incoming call is extended thereto.

The attendant may also originate calls to the central office by operating the talk key 331 and central office key 332. The operation of both these keys places ground on the tip side of the trunk for signaling purposes at the central office as described in connection with a local subscriber's call to the central office. Having obtained connection with the central office the attendant may extend connection to any local station in the manner described for an incoming call.

What is claimed is:

1. In a telephone system, telephone lines, a plurality of connecting means each individual to a different pair of said lines, registering mechanism comprising switch and relay recording devices, and means responsive to the joint setting of said switch and relay recording devices for operating one of said connecting means to interconnect the corresponding telephone lines.

2. In a telephone system, calling lines, a plurality of called lines, a plurality of connecting means each individual to a different pair of calling and called lines, registering means comprising step-by-step switch and relay recording devices, and means responsive to the joint settings of said switch and relay recording devices for operating said connecting means to thereby interconnect said calling and called lines.

3. In a telephone system, a calling line, a plurality of called lines, connecting means individual to said calling line and one of said called lines, a registering mechanism comprising a step-by-step switch set in accordance with impulses transmitted over said calling line and a relay recording device, and means responsive to the joint setting of said switch and relay devices for operating said connecting means to thereby establish a direct talking circuit between said calling line and said one of said called lines.

4. In a telephone system, a plurality of subscribers lines, a plurality of switch recording devices each individual to one of said lines, discriminating means individual to said one of said lines and comprising relays for recording a portion of a numerical designation, connecting means individual to a pair of said plurality of subscribers' lines, and means operable in accordance with the

joint setting of a switch recording device and said discriminating means for causing the operation of a particular one of said connecting means to establish a direct talking circuit between said pair of lines.

5. In a telephone system, a calling line, a called line, registering mechanism set in accordance with the complete designation of said called line, discriminating means individual to said calling line and operable in accordance with a portion of said designation of the called line, and connecting means individual to said calling line and to said called line and operable in accordance with the joint setting of said registering and discriminating means.

6. In a telephone system, a plurality of central office trunks, a subscriber's line circuit, controlling and registering mechanism associated with said line circuit, means operable in accordance with a special code dialled for associating said line circuit with an idle one of said central office trunks, and a plurality of connecting means each individual to a calling line and a central office trunk for connecting said line circuit directly with one of said trunks and for releasing the registering and controlling apparatus associated with said line circuit.

7. In a telephone system, a plurality of central office trunks, a plurality of called lines, a plurality of testing means each individual to a called line, a plurality of connecting means each individual to a central office trunk and a called line, and means operable upon the actuation of one of said testing means for testing the condition of a called line prior to the actuation of said connecting means.

8. In a telephone system, a plurality of calling lines, a plurality of called lines, a plurality of connecting means each individual to a calling and a called line, a plurality of testing means each individual to a calling line, a plurality of registering mechanisms, and means operable upon the setting of one of said registering mechanisms for causing the actuation of said testing means prior to the actuation of said connecting means.

In witness whereof, we hereunto subscribe our names this 27th day of November A. D. 1923.

WILLIAM H. MATTHIES.
WALTER P. ALBERT.
